UNITED STATES PATENT OFFICE.

JOHN HILARY PYNE BURCHETT, OF KEW GARDENS, ENGLAND.

INTERNAL-COMBUSTION ENGINE.

1,313,578.

Specification of Letters Patent.

Patented Aug. 13, 1919.

Application filed September 28, 1917. Serial No. 193,300.

To all whom it may concern:

Be it known that I, JOHN HILARY PYNE BURCHETT, of 38 Mortlake road, Kew Gardens, in the county of Surrey, England, have 5 invented certain new and useful Improvements in or Relating to Internal-Combustion Engines, of which the following is a specification.

This invention relates to internal combustion engines of the two stroke type. The 10 object of the invention is to provide an improved engine of this type.

A two stroke internal combustion engine made in accordance with this invention comprises a power cylinder, a crank case, a compression cylinder of larger diameter than the power cylinder disposed between the power cylinder and the crank case, said compression cylinder being provided for the 15 purpose of containing air or a mixture of air and fuel, which is subsequently forced into the power cylinder, a part thereof being at the same time utilized for admitting fuel into the power cylinder, and a piston, said 20 piston being provided at one end with a collar adapted to work with compression cylinder, while the other end works in the power cylinders, packing rings being provided at each end. Said collar being provided 25 for the purpose of forcing the air or mixture of air and fuel contained in the compression cylinder into the power cylinder, during the whole of the period in which the piston is traveling toward the head of the 30 cylinder. A sliding sleeve provided with an annular cavity is disposed internally on the trunk of the piston between the two ends and ports are provided in the trunk of the piston which are covered and uncovered and 35 connected together by the sliding sleeve. Said ports and annular cavity being provided for the purpose of leading the air or mixture of air and fuel contained in the compression cylinder into the power cylinder during 40 either the whole, or a predetermined percentage of the instroke, the residue of air contained in the compression cylinder in the latter case being then utilized for admitting fuel into the power cylinder toward the end 45 of the instroke in a manner hereinafter described. Means are provided for moving the sleeve in relation to the piston.

The drawing filed herewith is a diagrammatic section of one form of engine made in 50 accordance with this invention.

a is the power cylinder, *b* the compression

cylinder, *c* the crank case. One end *d* of the piston works in the power cylinder *a* and the collar *e* on the other end works in the compression cylinder *b*. In the trunk *f* of the piston are disposed inlet ports *g* and *g'* adapted to be covered and uncovered and connected by a sliding sleeve *h*. In the sleeve *h* is a channel *h'* adapted to connect the ports *g* and *g'*. In the piston *d* is an annular passage *d'* and ports *d''* adapted to connect the cylinder *b* to the cylinder *a*. On the sleeve *h* is a rack *j*. On the small end of the connecting rod *k* is a toothed segment *m* which gears with the rack *j*. *n* is the exhaust port. 60 *o* is a scavenging air port connecting with the crank case *c*. In the crank case is disposed a non-return valve *p*.

The direction of rotation is indicated by the arrow. In the drawing the piston and sleeve are shown in the position they would occupy on the power stroke with the inlet port *g* open and the port *g'* closed. In operation during the outstroke air or carbureted mixture is admitted from the crank case to 75 the cylinder *b* through the port *g*. Toward the end of the outstroke, the sleeve "H" is moved by means of the segment *m* and rack *j* so as to place the channel *h'* in communication with the port *g*, thereby closing this 80 port to the crank case and placing it in communication with the port *g'* and the annular passage *d'*. During the major portion of the instroke, the air or mixture contained in the cylinder *b* is passed to the cylinder *a* 85 via the ports *g*, *g'*, channel *h'* and annular space *d'*. Toward the end of the instroke, the sleeve *h* is again moved so as to close the port *g'* and reopen the port *g* to the crank case, and the cycle proceeds as before. 90 On the instroke the air or mixture is passed from cylinder *b* to cylinder *a* through the port *g'*.

The exhaust takes place through the ports *n* uncovered by the piston at the end of the 100 power stroke. Compressed air or carbureted mixture is at the same time admitted through the port *o* on the opposite side of the cylinder for the purpose of assisting in the expulsion of the exhaust gases. A 105 spring-pressed valve *s* is disposed between the chamber *R'* and the top of the power cylinder *a*.

In the form of engine shown in the drawing herewith, the port *g* is so arranged as to 110 be closed by the walls of the power cylinder at a predetermined moment prior to the

completion of the instroke, and the air thereby entrapped in the compression cylinder is utilized to admit fuel into the power cylinder in the following manner: At the top of the 5 power cylinder is a cavity adapted to receive a plug R, said plug being provided with a chamber R' adapted to receive air from the compression cylinder b, and a chamber R² adapted to receive fuel through the fuel 10 inlet R³. A spring pressed valve S is disposed between the chamber R' and the top of the power cylinder a. From the chamber R² is a duct or ducts r leading to jets in the seating of the non-return spring pressed 15 valve s. From the chamber R' is a pipe or channel t leading to the top of the compression cylinder b. In operation, the fuel is fed under high pressure to the chamber R² and when the ports g in the trunk piston 20 are covered toward the end of the instroke by the walls of the power cylinder, the remainder of the air in the compression cylinder is forced through the pipe t, causing the non-return valve s to open and allow 25 some fuel to pass through the ducts r and jets into the power cylinder.

Regulation is effected either by varying the pressure in the fuel reservoir or by closing more or less of the jets through which 30 the oil is forced, or the fuel may be injected by any other suitable arrangement depending either upon a direct oil pump or a high pressure oil reservoir with a mechanically operated injection valve. Or for suf- 35 ficiently volatile oils a carbureter may be employed disposed in such a manner that the air drawn into the crank case through the non-return valve p must pass first through said carbureter.

40 It is evident that by suitably proportioning the relative diameters of the cylinders a and b and provided the clearance around the sleeve h and between the end e of the piston and the cylinder are reduced to a 45 minimum, it would be possible to squeeze into the cylinder a whatever quantity of new air or mixture might be found most suitable and depending in any particular case upon whether efficiency of fuel con- 50 sumption or power per unit weight of engine was the more important consideration.

What I claim as my invention and desire to secure by Letters Patent is:—

1. A two stroke cycle internal combustion 55 engine comprising a power cylinder, a crank case, a compression cylinder, of larger diameter than the power cylinder, disposed between the power cylinder and the crank case, said compression cylinder being pro- 60 vided for the purpose of containing air or a mixture of air and fuel which is forced into the power cylinder and a part of which is utilized for forcing fuel into the power cylinder, a trunk piston working in said 65 cylinders, said piston being provided with

packing rings at each end, one end working in the power cylinder and the other end being provided with a collar adapted to work in the compression cylinder, said collar being provided for the purpose of forcing 70 the air or mixture of air and fuel contained in the compression cylinder into the power cylinder, ports in said piston, a sleeve in said piston, a channel in said sleeve adapted to connect the ports in said piston; said 75 ports being provided to lead the air contained in the compression cylinder to the power cylinder during the major part of the instroke, and means for moving the sleeve in relation to said piston. 80

2. A two stroke cycle internal combustion engine comprising a power cylinder, a crank case, a compression cylinder, of larger diameter than the power cylinder, disposed between the power cylinder and the crank 85 case; said compression cylinder being pro- 90 vided for the purpose of containing air or a mixture of air and fuel which is forced into the power cylinder, and a part utilized for forcing fuel into the power cylinder, 95 a trunk piston working in said cylinders, said piston being provided with packing rings at each end, one end working in the power cylinder and the other end being provided with a collar adapted to work in the 100 compression cylinders, said collars being provided for the purpose of forcing the air or mixture of air and fuel contained in the compression cylinder into the power cylinder ports in said piston, a sleeve in 105 said piston, a channel in said sleeve adapted to connect the ports in said piston, said ports being provided to lead the air contained in the compression cylinder to the power cylinder during the major part of the instroke, means for moving the sleeve in relation to the piston, fuel admission jets at the top of the power cylinder and means for injecting fuel through said jets. 110

3. A two stroke cycle internal combustion engine comprising a power cylinder, a crank case, a compression cylinder of larger diameter than the power cylinder, disposed between the power cylinder and the crank case, said compression cylinder being provided for the purpose of containing air or a mixture of air and fuel which is forced into the power cylinder and a part utilized for forcing fuel into the power cylinder, a trunk piston working in said cylinders, said piston being provided with packing rings at each end, one end working in the power cylinder and the other end being provided with a collar adapted to work in the compression cylinder, said collar being provided for the purpose of forcing the air or mixture of air and fuel contained in the compression cylinder into the power cylinder ports in said piston, a sleeve in 120 said piston, a channel in said sleeve 125 in said piston, a channel in said sleeve 130

- adapted to connect the ports in said piston, said ports being provided to lead the air contained in the compression cylinder to the power cylinder during the major part
5 of the instroke, means for moving the sleeve in relation to said piston, a plug disposed in a cavity at the top of said power cylinder, said plug being provided with a chamber adapted to receive air and a chamber
10 adapted to receive fuel, means for admitting fuel under pressure to said fuel cavity, a spring pressed non-return valve in said air
chamber, ducts from said oil chamber to the seating of said valve and a duct from said chamber to the top of the compression 15 cylinder.

In witness whereof, I have hereunto signed my name in the presence of two subscribing witnesses.
